Primary Examiner — Michael A Pratt(74) *Attorney, Agent, or Firm* — Vidas, Arrett & Steinkraus(57) **CLAIM**

The ornamental design for a firearm trigger, as shown and described.

DESCRIPTION

FIG. 1 is a front angled isometric view of the firearm trigger; FIG. 2 is a rear angled isometric view of the firearm trigger; FIG. 3 is a right side view of the firearm trigger; FIG. 4 is a left side view of the firearm trigger; FIG. 5 is a rear view of the firearm trigger; FIG. 6 is a front view of the firearm trigger; FIG. 7 is a top view of the firearm trigger; and, FIG. 8 is a bottom view of the firearm trigger.

Broken lines in the Figures show boundaries or environmental structure. The broken lines are not part of the claimed design.

1 Claim, 5 Drawing Sheets(56)
